TWO-PART PLASTIC CONTAINER

Thomas V. Paulson, Rte. 2, Box 198, Fallbrook, Calif.
Filed May 19, 1960, Ser. No. 30,254
1 Claim. (Cl. 220—4)

2

wall 12 or 13, preferably at the intersection thereof, to serve as a guide to effect interfitting neck of the main wall of the complementary section when the container sections are in closed relation.

5 Assembly and separation of the container sections should be clear from FIGURES 1 and 2, and it will be apparent that the side walls 12 have a sufficient degree of flexibility so that when the two sections are brought together nibs 19 will, when being moved into engagement in recesses 17, flex the complementary auxiliary wall 14, this action being expedited by bevels 18. When the container sections are in interengaged relation, a main wall portion will be disposed between abutments 20 and auxiliary walls 14, and perfect alignment of the sections will result. The sections may be separated by the application of inward pressure applied above nibs 19 on the opposite sides of main wall 12 of one of the sections, for example, section 10 whereby the nibs of this section will be released from grooves 17 of the complementary section 11, and the two sections readily separated.

10 From the foregoing description it will be clear that the hereinabove objects and advantages of this invention have been achieved, however, changes and modifications may be made without departing from the spirit and scope of 15 the subjoined claim.

20 Having described my invention, what I claim is:

25 A container comprising two identical, separable, flexible, resilient molded plastic rectangular sections fitting together in mutual telescopic relation, each section having a continuous main wall and a pair of auxiliary walls at diagonal corners, the main walls of said sections being in aligned abutting relation, said auxiliary walls being offset outwardly and each extending substantially halfway along two converging sides of said main wall, the ends 30 of said auxiliary walls being beveled and being in aligned abutting relation with the corresponding auxiliary wall ends of the complementary section when the sections are fitted together, there being a post-like abutment on the inner side of each main wall at said diagonal corners and 35 extending beyond the edge thereof to effect alignment of said sections when being assembled, and nib and socket means for locking said sections together.
